UNITED STATES PATENT OFFICE.

FREDERICK M. WHITE AND HENRY E. RIEGER, OF SAN DIEGO, CALIFORNIA.

APPARATUS FOR COVERING SUBMERGED FILES WITH CONCRETE.

1,202,134.

Specification of Letters Patent. Patented Oct. 24, 1916.

Application filed July 3, 1916. Serial No. 107,289.

To all whom it may concern:

Be it known that we, FREDERICK M. WHITE and HENRY E. RIEGER, citizens of the United States, residing at San Diego, in the county 5 of San Diego and State of California, have invented certain new and useful Improvements in Apparatus for Covering Submerged Piles with Concrete, of which the following is a specification.

10 Our invention relates to an apparatus to be used for molding a layer of concrete around piles which are driven and partially submerged, and the objects of our invention are: first, to provide an apparatus of this 15 class by the use of which a layer of concrete of suitable thickness may be formed around a pile which is partially submerged so that the concrete layer will extend some distance into the ground and above the surface 20 face of the water; second, to provide an apparatus of this class by the use of which the concrete may be mixed and poured above the surface of the water and lowered in position around the pile to the position desired; 25 third, to provide an apparatus of this class which prevents contact of the water from the outside with the concrete thus providing a concrete shell around the pile which is of uniform thickness and hardness; fourth, to 30 provide an apparatus of this class which is easily and readily removed after the concrete has been allowed to set sufficiently; and fifth, to provide an apparatus of this class which is simple and economical of construction, durable, easy to operate, easy to install 35 and will not readily get out of order.

With these and other objects in view as will appear hereinafter our invention consists of certain novel features of construction, 40 combination and arrangement of parts as will be hereinafter described in detail and particularly set forth in the appended claims, reference being had to the accompanying drawings and to the characters of 45 reference thereon which form a part of this specification, in which:

Figure 1 is a perspective view of a fragmentary portion of a driven pile and showing encircling the same the layer of concrete 50 and showing a fragmentary portion of our apparatus positioned thereon. Fig. 2 is a perspective view of several fragmentary portions of the forms showing the means for joining the separate form members together. Fig. 3 is an inside elevational view of two of the lower trap members. Fig. 4 is

a top view thereof. Fig. 5 is a side elevational view of a fragmentary portion of the upper ends of the form members 3, and Fig. 6 is a perspective view of the key for connecting the different form members together.

Similar characters of reference refer to similar parts throughout the several views.

The rigid trap members 1, mold members 2, mold members 3, releasing rods 4, key members 5, vertical gaskets 6, horizontal gaskets 7, flexible trap members 8, cables 9 and cables 10 constitute the principal parts of our apparatus.

The rigid trap members 1 are quadrant in 70 form so that four of them when connected together form an annular plate. They each consist of a quadrant shaped metallic plate 1 and each is provided on its outer surface with an angle lug 1^a, the one member of 75 which is secured to said plate 1 and the other member extends therefrom and is provided with a slotted hole 1^b therein. On the other edge of the plate is secured a similar lug 1^c which is provided with a U shaped lug 1^d 80 on its extended member adapted to fit into the hole 1^b in one of the lugs 1^a on another of the mold members 1 and one of the key members 5 is inserted therein for securing said mold members together and mounted 85 between the adjacent edges of the molding members 1 are gaskets 1^e which are preferably the combination of rubber and canvas to provide strength and pliability. These key members 5 connecting the members 1 90 together are removed by the cable 9 which connects with them so as to pull one and then the other of said keys 5. Secured in the middle near the lower edge of each of the said members 1 is a U shaped lug 1^f in 95 which is mounted a ring 1^g and mounted in the middle near the top edge of each of said members 1 is a lug 1^h which is provided with a hole therethrough for the pin 2^e for connecting the sections 1 and 2 together.

100 Mounted on the inner surface of each of the members 1 is an angle bar 1ⁱ, the one member of which is secured to the inner surface of said mold member 1 and the other member extends inwardly and upon the top surface of which is secured one of the flexible trap members 8, the inner edge of which extends considerably past the inner edge of the angle member and one end of said flexible trap member 8 extends past the end of 110 said angle member so that it over-laps a similar member on an adjoining trap mem-

ber. These flexible trap members 8 are preferably composed of a composition of rubber and canvas to provide strength, durability and flexibility.

5 The mold members 2 consist of semi-circular plates 2 which are provided with angle bars 2^a on the top and side edges thereof which are secured thereto and the extending members of each of said angle bars are provided with oblong holes 2^b on one of said mold members and on the opposite mold member they are provided with U shaped lugs 2^c which are adapted to fit in said oblong holes and extend through the same 10 and between the angle bar and the extended portion of said lug is mounted one of the key members 5 in each of said U shaped lugs.

15 Mounted between the angle bars 2^a on the separate halves are vertical gasket 6 which provide a water-tight fit between said angle bars. Secured to the inner surface of said plate 2 at the lower side thereof is a metallic piece 2^d which extends downwardly into the trap members and for reinforcing and making a tight joint. Mounted near the lower sides of said mold members 2 are bifurcated lugs 2^e which are provided with slots therein adapted for the pins 2^f so that the lugs 2^e, 1^h and pin 2^f form hinges for pivotally 20 connecting the members 1 and 2 together which, however, will release when the members 1 are turned upwardly thereon.

25 Mounted between the adjacent edges are gaskets 7 for forming a water-tight joint between said members. Mounted in the middle of each of the form members 2 near the top are hook shaped lugs 2^g adapted for a hitch for cables 10, one on each side of the pile for guiding and supporting said forms 30 around the pile as it moves downwardly as each section is filled with concrete between the forms and the driven pile. The concrete we have marked A and the pile B to facilitate the illustration.

35 The form members 3 which comprise the remaining form members are shaped and constructed the same as the member 2 except that on the lower edge there is mounted an angle bar as well as on the top and side edges and the joints between the members 2 and 3 are formed by means of the holes 3^a and U shaped lugs 2^c and one of the keys 5 driven therein there being a gasket 7 between the two horizontal angle bars and the 40 pieces 2^d are not placed thereon. In order to remove the keys 5 along the vertical angle bars there are provided rods 4 which extend through the links connected to said keys and the lower ends of said rods 4 are provided with bends 4^a therein so that the said keys may be removed by raising said rods 4, the upper end of which extends above the top of the water.

45 Though we have shown and described a particular construction, combination and ar-

50 rangement of parts we do not wish to be limited to this particular construction, combination and arrangement, but desire to include in the purview of our invention the construction, combination and arrangement substantially as set forth in the appended claims.

55 The operation of the apparatus is as follows: The trap members 1 are connected together around the pile above the surface of the water and secured by means of keys in the U lugs 1^d the inner edge of the flexible trap members 8 are bent upwardly, and fit snugly around the pile. The two members 2 are then pivotally mounted upon this member by means of the lugs 1^h, 2^f and pins 2^e and the metallic pieces 2^d extend down inside the trap members to adjacent the top edges of the angle 1^f and the two members 2 are secured together by means of the keys in the vertical angle bars. The form is supported by means of the cables 10, one on each side in the lugs 2^g and the space between the pile and forms is filled with concrete the lower edge supported on the trap members 8. When the forms 2 are nearly full the forms 3 are secured to the top edge thereof, by means of the keys and lugs through the angle bars and the two members are secured together by means of the keys in the lugs along the vertical angle bars. Then the lower members are lowered into the water and the sections 3 filled and so on until the trap members 1 reach the ground when the keys securing said trap members together are removed by means of the cables 9 and the lower edge of the trap section is turned upwardly on the pins 2^f which releases the trap members at the bottom and the plate 2^d together with the concrete is allowed to sink into the ground around said pile, the weight of the layer of concrete and pile forcing the same into the ground some distance. After the concrete has set sufficiently the keys along the vertical angle bars are removed by means of the rods 4 and the lower members 2 and 3 are then raised to the surface of the water by means of the cable 10, the members 3 being removed by removing the keys after the joints are raised to above the surface of the water thus leaving a layer of concrete around the pile from some distance below the top of the ground to above the surface of the water.

60 It is obvious that with the above apparatus there is provided a means whereby a layer of concrete may be lowered around wooden or other piles driven into the ground and in several feet of water, that the molds and joints are so constructed that the water from the outside cannot get through to the concrete in sufficient quantity to injure it until it has set, that the different mold sections are readily assembled and may be 65

readily disassembled although submerged, that the apparatus as a whole is simple and economical of construction, durable, easy to operate and will not readily get out of order.

5 Having thus described our invention what we claim as new and desire to secure by Letters Patent, is:

1. In an apparatus of the class described, the combination of a plurality of members 10 forming an annular trap member, a flexible member secured thereto near the bottom extending inwardly adapted to press tightly against the pile, a pair of semi-circular form members provided with hinged members 15 thereon adapted to be pivotally secured near the top edges of said annular piece, means for securing said semi-circular form members together and means for forming a tight joint between said members.
- 20 2. In an apparatus of the class described, the combination of a plurality of members forming an annular trap member, a flexible member secured thereto near the bottom extending inwardly adapted to press tightly 25 against the pile, a pair of semi-circular form members provided with hinged members thereon adapted to be pivotally secured near the top edges of said annular piece, means for securing said semi-circular form members 30 together, means for forming a tight joint between said members, and means for readily removing said connecting means.

3. In an apparatus of the class described, the combination of a trap member comprising 35 a plurality of sections, means for readily connecting said sections together and for releasing the same, a pair of semi-circular form members pivotally mounted thereon, means for securing said form members together and forming a tight joint between 40 the same.

4. In an apparatus of the class described, the combination of a trap member comprising a plurality of sections, means for readily 45 connecting said sections together and for releasing the same, a pair of semi-circular form members pivotally mounted thereon, means for securing said form members together and forming a tight joint between 50 the same, and other semi-circular form members secured to the top ends of said first mentioned form members and similar means secured to said last mentioned form members for securing them together and 55 forming a tight joint.

5. In an apparatus of the class described, the combination of a trap member comprising a plurality of sections, means for readily connecting said sections together, means 60 for releasing the same, a pair of semi-

circular form members pivotally mounted thereon, means for securing said form members together, means for forming a tight joint between the same, other semi-circular form members secured to the top ends of 65 said first mentioned form members and similar means secured to said last mentioned form members for securing them together and forming a tight joint and means for readily releasing said securing means so 70 that said form members will be readily separated from each other.

6. In an apparatus of the class described the combination of a trap member comprising a plurality of sections, means for readily connecting said sections together and for releasing the same, a pair of semi-circular form members pivotally mounted thereon, means for securing said form members together and forming a tight joint between the same, other semi-circular form members secured to the top ends of 75 said first mentioned form members and similar means secured to said last mentioned form members for securing them together and 80 forming a tight joint, means for readily releasing said securing means so that said form members will be readily separated from each other and a cable secured to each of said sections for raising the same to 85 above the surface of the water.

7. In an apparatus of the class described the combination of a plurality of form sections, means for readily securing them together, means for readily separating them, 95 means for supporting them in position around a pile and a trap pivotally connected to the lower end thereof made in readily separable sections provided with inwardly extending flexible members adapted to fit 100 the pile snugly for supporting the concrete between said pile and said form sections.

8. In an apparatus of the class described the combination of a plurality of form sections, means for readily securing them together, means for readily separating them, means for supporting them in position around a pile, a trap pivotally connected to the lower end thereof made in readily separable sections provided with inwardly 105 extending flexible members adapted to fit the pile snugly for supporting the concrete between said pile and said form sections and means extending to above the surface of the water for releasing and removing said trap. 110

In testimony whereof, we have hereunto set our hands, at San Diego, California, this 26th day of June, 1916.

FREDERICK M. WHITE.
HENRY E. RIEGER.
